UNITED STATES PATENT OFFICE.

WESTON F. BRIGHT, OF LONGMEADOW, MASSACHUSETTS.

EMBROIDERY FRAME.

Application filed March 10, 1927. Serial No. 174,256.

This invention relates to improvements in supports or stands for embroidery hoops.

According to the novel features of the invention, I provide a device comprising a pair of embroidery hoops embracing members which are connected in such a manner that they may be moved relative to one another for any desired relative angular position, whereby one of said members may be utilized 10 to support the other while the latter may carry and support an embroidery hoop and the work being done thereon.

The invention may be practiced in various ways and I do not therefore wish to be limited 15 by the specific form shown and described, the form shown being intended merely to disclose a preferred form of the invention.

In the drawings:

Fig. 1 is a perspective view showing hoop 20 embracing members in an open spaced apart position; and

Fig. 2 is a view showing the members in closed position.

Referring to the drawings in detail, 1 and 25 2 represent frame or hoop embracing members which are preferably formed by bending a strip of spring like material such as certain kinds of steel, brass or the like into the form of a circle. The ends 1' and 2' of the strips 30 are bent inwardly as shown and are preferably spaced apart so as to provide an open space therebetween to allow for an inwardly yielding movement of the frames for the purpose later to be described.

35 Connecting bars or arms 3, preferably of rigid material, have their opposite ends connected to the ends 1' and 2' of the frame members 1 and 2, preferably by rivets or the like, so as to permit a relative pivotal action of said members and bars. The pivotal connections 40 may take any form desired but will preferably be such as will permit a free pivotal action and at the same time tend to hold the parts in any position of relative adjustment.

45 When not in use, the members 1 and 2 may be moved on their respective pivots to superposed or collapsed position shown in Fig. 2 and will in that position occupy but a small amount of space as will be observed.

50 To embrace an embroidery hoop which usually comprises a pair of interfitting hoop members adapted to engage therebetween the cloth to be embroidered, the bars 3 may be

grasped by the hand and pressed towards one another against the spring action of the frames to thereby compress the frame or frames 1 and 2. In the compressed condition, a frame may be inserted within the inner hoop of a pair and the bars 3 released so that the frame will expand within the hoop to embrace the same and hold it securely. The other of the frames may be set upon the embroiderer's lap, table or the like, to serve as a stand, and the one supporting the hoop moved with respect thereto in any desired angle 65 which may be most convenient for the embroiderer.

If desired, different portions of the cloth to be embroidered may be inserted between different hoops and embraced by the separate 70 frames so that said portions may be moved into relative positions for observation or the like. By grasping the bars at one end or the other, it is possible to compress either one of the frames so that one may be disengaged 75 from the hoop or the like without disturbing the other.

From the foregoing, it will be observed that I have provided a device that is simple in construction and which may be adjusted to position the work as will be most convenient 80 for the embroidery worker.

Having described my invention in the form at present preferred, what I now claim is:

1. The combination in an embroidery hoop 85 support of a pair of resilient hoop members for engaging the inner surfaces of embroidery hoops each having their inner ends bent inwardly and link bars having their opposite ends pivotally connected to the said inner 90 ends of the resilient hoop members.

2. An embroidery hoop support comprising in combination, a pair of resilient hoop members each having unjoined ends which are turned inwardly in spaced relation so as 95 to yieldingly embrace the inner surfaces of an embroidery hoop, and link members pivotally connecting the unjoined ends of one hoop with those of the other whereby the hoops may be moved relatively to one another. 100

3. A support for an embroidery hoop or the like comprising in combination, a pair of resilient members having their opposite ends turned inwardly and spaced from one another and the portion intermediate said ends formed 105 so as to engage an embroidery hoop and links

pivotedly connected to both ends of said members whereby they may be moved relative to one another.

4. A support for an embroidery hoop or the like comprising in combination, a pair of resilient hoop members each having their opposite ends unjoined and spaced apart whereby each may engage the periphery of an em-

broidery hoop independent of the other and links pivoted at their opposite ends to the ends of said hoop members whereby the members may move relative to one another. 10

In testimony whereof I have affixed my signature.

WESTON F. BRIGHT.
